S. W. FARBER.
ELECTRIC LAMP FIXTURE.
APPLICATION FILED APR. 2, 1917.

1,266,341.

Patented May 14, 1918.

UNITED STATES PATENT OFFICE.

SIMON W. FARBER, OF BROOKLYN, NEW YORK.

ELECTRIC-LAMP FIXTURE.

1,266,241.

Specification of Letters Patent. Patented May 14, 1918.

Application filed April 3, 1917. Serial No. 159,595.

To all whom it may concern:

Be it known that I, SIMON W. FARBER, a citizen of the United States, and residing in the county of Kings, city of New York, State of New York, have invented certain new and useful Improvements in Electric-Lamp Fixtures, of which the following is a correct and complete specification.

The object of my invention is to make a fixture for electric lamps, which shall be simply, quickly, and cheaply constructed, and which shall be capable of fastening the lamp to a variety of objects in a number of different positions and angles, and shall also be capable of serving as a stand for the lamp upon any convenient support. Other objects of my invention will be described in the following description and drawings which represent a preferred embodiment of my invention.

Figure 1 represents a side elevation of my new and improved fixture.

Fig. 2 is a side elevation of the fixture, showing the lamp in an inclined position.

Fig. 3 shows the fixture fastening the lamp in a horizontal position to an upright rod.

Fig. 4 is a top view of the clamp forming the bottom of the fixture.

Fig. 5 is a side elevation showing a detail view of the bottom of the fixture.

Fig. 6 is a sectional view on line 6—6 of Fig. 5 in the direction of the arrow.

Fig. 7 is an end view of the bottom of the fixture.

Similar letters of reference indicate similar parts in all the figures.

The fixture is made up of an upper limb 2 hingedly connected to a lower limb 5 by the screw 3, which can be tightened so as to keep the limbs 2 and 5 at any desired angle, as shown in Fig. 2.

The limb 2 is provided at its top with a socket of the ordinary and well-known kind, which is not shown and is not a part of my improvement in itself, for receiving an incandescent lamp of the ordinary and well-known kind. The top of the limb 2 is also provided with a reflector 1 of the well-known type, and which may be rotated about the limb 2 as an axis.

The electric wires 11 communicate with a

hole in the limb 5 and pass through it into the limb 2, where connection is made with the lamp in the ordinary way.

The limb 5 is fastened at its bottom to a combination clamp and support consisting of the like members 8 and 9. These members each consist, as shown in Fig. 6, of a strip of metal having a broad flat part bent up and then bent into an arcuate form. The bottom of the arc is in the same line as the flat surface, so that the bottom member 9 of the clamp forms a substantial and firm surface upon which the fixture may rest upon any suitable object 7, as a desk or the like.

From each member 8 and 9 two tongues 18 and 19 are respectively stamped out, so that two spaces 13 are formed in each of them, these spaces 13 being separated by a bridge 14.

Each of the members 8 and 9 can be stamped out into shape at one blow of the die.

The tongues 18 and 19 are perforated so that, when they are respectively bent outwardly away from the surface of the metal, or inwardly toward it, so as to enable the halves 8 and 9 to be connected, a spindle 21 can be thrust in, as shown in Fig. 7. This spindle 21 carries the spring 12 having a rearwardly bent arch 17 at its upper end, pressing against 8, and rearwardly bent ends 20, pressing against 9, so as to maintain the clamping members 8 and 9 together.

The spindle 21 is screw-threaded at its ends, and is kept in position by nuts 6, fastened thereto at each end.

The member 9 has a hole 16 at its rear, so that it can be hung on a nail or the like. It has a cloth 10 fastened to its bottom, and the inside of the arcuate portions of the clamping members are also lined with cloth 10.

The bottom of the limb 5 is fastened to the bridge 14, by means of two tongues 15, integral with limb 5, and which are bent under and pressed against bridge 14 at each side thereof.

The current is switched on and off by a button 4.

The entire fixture is made of a minimum number of parts, and can serve to support the lamp upon a desk, or clamp it to a bed or the like.

I have described one embodiment of my invention, but it is obvious that changes could be made without departing from the spirit thereof, as embodied in the appended 5 claims. Any suitable material other than metal could be used, as wood, celluloid, or the like.

I claim:

1. An electric lamp fixture having as a base two clamping members of like construction, each clamping member being composed of a sheet of metal having a flat rear portion and an arcuate forward portion, each clamping member having two tongues 10 stamped out of said flat rear portion at substantially right angles thereto, the slots formed by stamping out said tongues having an intermediate bridge-like portion formed in the center of each clamping member, said tongues being connected by a pintle, spring means for forcing said clamping members together and a standard adapted to support an incandescent lamp connected to said bridge-like portion.
2. An electric lamp fixture comprising two clamping members of like construction, each clamping member being composed of a sheet of metal having a flat rear portion and an arcuate forward portion, the exterior 20 of said arcuate portion being in line with said flat rear portion, each clamping member having two tongues stamped out of said flat rear portion at substantially right angles thereto, the slots formed by stamping out 25 said tongues leaving an intermediate bridge-like portion in the center of said clamping members, said tongues being connected by a pintle, spring means for forcing said clamping members together and a standard

adapted to support an incandescent lamp 40 connected to said bridge-like portion.

3. An electric lamp fixture having as a base a pair of equal and complementary clamping jaws connected together by a spring, each clamping jaw being composed 45 of a sheet of metal having a flat rear portion and an arcuate forward portion so that one of said clamping jaws forms a substantially horizontal supporting base, and a standard adapted to support an incandescent lamp 50 fixed in the center of said clamping members and perpendicular thereto.

4. An electric lamp fixture comprising a support composed of clamping members connected to each other, means for forcing 55 the said clamping members together, each of said clamping members having adjacent perforations and an intermediate bridge-like portion in the center of said clamping members and a standard connected to the 60 said bridge-like portion by means of tongues connected to the said standard and bent under the said bridge-like portions to tightly clamp it, the said standard being adapted to carry an incandescent lamp, the center of 65 gravity of said fixture being sufficiently far from the edges of said clamping members so that when the lamp is bent over the said standard remains substantially at right angles 70 to the surface upon which the said clamping members are resting.

In testimony that I claim the foregoing as my invention, have signed my name in presence of two subscribing witnesses.

SIMON W. FARBER.
